(57) **CLAIM**

The ornamental design for a razor, as shown and described.

DESCRIPTION

FIG. 1 is a perspective view of a razor showing the new design;

FIG. 2 is a front view thereof;

FIG. 3 is a rear view thereof;

FIG. 4 is a left side view thereof; a right side view is a mirror image with the left side view thereof;

FIG. 5 is a top view thereof; and,

FIG. 6 is a bottom view thereof.

The evenly-dashed broken lines illustrate portions of the razor that form no part of the claimed design.

The dot-dash broken lines represent the boundary line of the razor and form no part of the claimed design.
